KARL SCHWEIZER, OF STUTTGART, GERMANY, ASSIGNOR TO ROBERT BOSCH
AKTIENGESELLSCHAFT, OF STUTTGART, GERMANY.

AUTOMATIC CONTROL DEVICE

Application filed March 21, 1930, Serial No. 437,782, and in Germany June 29, 1930.

This invention relates to improvements in automatic control devices for ignition arrangements of internal combustion engines in which the time of ignition is varied according to the velocity of centrifugal governor weights.

In such apparatus the centrifugal governor weights in addition to the loading due to the moment of rotation of the governor must also constantly overcome a centripetal spring force, which tends to return them into their position of rest. The return action of this spring operates over a very wide range as the control range of regulators of this type is very considerable.

This is attained according to this invention by using helical springs as return springs which are deflected by the weights substantially transversely to their longitudinal axis. In this method of tensioning, the springs themselves at first offer only a small resistance in spite of considerable tension; this resistance, however, increases with the increasing deflection of the spring. The regulation curve of a regulator with springs tensioned in this manner is particularly good if irrespective of the lever arms, the return force of the centrifugal weights is increased with increased throw of the weights.

One form of construction of the invention is illustrated by way of example, in the drawing in which

Figure 1 is a drum governor bowl in longitudinal section.

Figure 2 is a plan view of the governor in the position of rest.

Figure 3 is plan view of a governor in working position of the parts.

Secured to the driving shaft 1, is a flange 2, on which rests the base plate 3 of the governor. Mounted on the base plate are four pins 4 and 5, between which two helical springs 6, are tensioned. The pins 4 act as bearings for two centrifugal weights 7. Mounted on the centrifugal weights by two screws 8, are curved elements 9, which operate the variation of the ignition tuning by their inertia and the shape of their curved sides 10. As clearly shown in Figure 1, cam elements 9 are secured to the top faces of weights 7 by two

spaced screws 8. On the weights 7, are slots 11 in which slide adjusting pins 12. The displaceable sleeve 14 is mounted on the reduced end 13, of the shaft 1, which sleeve is integral with the cam 15, for the make and break and with the guide 16 for the rotating distributor. The lower part of this sleeve is extended to form the pins 12.

The mode of operation of the regulator is clearly shown in Figures 2 and 3.

I declare that what I claim is:

1. A centrifugal governor comprising in combination a driving part, a driven part, centrifugally movable weights on one of said parts, a connection between said weights and the other part, coil tension springs between the pivot journals of said weights and the part on which they are mounted, and means to deflect said springs substantially transversely to their longitudinal axes on the displacement of the weights. 70

2. A centrifugal governor comprising in combination a driving part, a driven part, centrifugally movable weights on one of said parts, cam surfaces on said weights, a connection between said weights and the other part, tension coil springs mounted on the part on which said weights are mounted and arranged to be deflected by said cam surfaces transversely to their longitudinal axes 80 upon displacement of said parts. 75

3. A centrifugal governor comprising in combination a driving part, a driven part, centrifugally movable weights on one of said parts, cam surfaces on said weights, a connection between said weights and the other part, tension coil springs mounted between the pivot journals of said weights and the part on which they are mounted and arranged to be deflected transversely of their longitudinal axis by said cam surfaces with increasing leverage according to increase of movement of said weights due to centrifugal force. 90

4. A centrifugal governor comprising in combination a driving part, a driven part, centrifugally movable weights on one of said parts, a connection between said weights and the other part, springs between two pins on the driving part, and means to deflect said 100

springs substantially transversely to their longitudinal axes on the displacement of the weights.

5. As an article of manufacture a centrifugal governor for variation of timing of internal combustion engines comprising in combination a driving shaft, a plate on said shaft, pivot pins on said plate, centrifugally movable weights pivoted on said pins, cam surfaces on said weights, coil tension springs between the pivot journals of said weights and said plate adapted to be deflected substantially transversely of their longitudinal axis by said cam surfaces, a driven part, pins on said driven part engaging in slots formed in said weights, a cam on said driven part for controlling an electrical make-and-break, and a connection on said driven part to an electrical distributor.

20. A centrifugal governor comprising a driving member, a driven member, centrifugal weights pivotally mounted on said driving member, resilient means opposed to the action of said centrifugal weights, and cam means for displacing said resilient means, said cam means being so shaped as to increase the force exerted by the resilient means more rapidly than the increase of the force due to centrifugal weights with the increase of rotational speeds of the driving member.

30. In testimony whereof I have hereunto affixed my signature.

KARL SCHWEIZER.
